UNITED STATES PATENT OFFICE

2,458,948

PROTECTIVE DEVICE

George F. Lincks, Pittsfield, Mass., assignor to
 General Electric Company, a corporation of
 New York

Application March 21, 1945, Serial No. 583,960

8 Claims. (Cl. 200—133)

1

My invention relates to a protective device, and more particularly to a fuse protective device for protecting electrical apparatus such as transformers and the like which may be of the liquid insulation-filled type. Specifically my invention is an improvement on United States Letters Patent 2,337,353, Smith, granted December 21, 1943, and assigned to the same assignee as the present application.

Electrical devices, such as distribution transformers and the like, often have fuses or the like mounted within the transformer itself. When these fuses were mounted in the transformer it was necessary to employ fusible elements, sometimes called "weak links," having relatively high ratings to insure against their rupturing or blowing except in the case of an internal fault in the electrical device. In such a case it was necessary to recondition the transformer so if the fusible elements only blew under such conditions there would be no objection to taking the transformer to a service shop to replace the fuse since it must be taken to the service shop anyway. However, service experience has shown it necessary to use lower rated fuse links so that there will be sufficient current to cause the fusible element to melt when the electrical device is located out toward the end of long lines, and also so as properly to sectionalize the primary lines to maintain the desired continuity of service. In order to employ fuses with sufficiently low ratings to meet these requirements it is not only desirable but imperative to be able to renew or replace these fuses in the field without sending the transformer back to a shop or factory.

It is an object of my invention to provide a new and improved renewable bushing fuse of the expulsion type.

It is another object of my invention to provide a renewable bushing fuse of the expulsion type with means for elongating the arc in the liquid dielectric so as quickly to interrupt the circuit.

It is another object of my invention to provide a bushing fuse which may readily be replaced in the field which is simple and compact and inexpensive to manufacture.

Further objects and advantages of my invention will become apparent as the following description proceeds and the features of novelty which characterize my invention will be pointed out with particularity in the claims annexed to and forming a part of this specification.

For a better understanding of my invention reference may be had to the accompanying draw-

ing in which Fig. 1 is a sectional view of the bushing of a transformer illustrating the fused protective device of my invention; Fig. 2 is an enlarged view of a resilient member which forms the lower contact to which the bushing fuse is connected; Fig. 3 is a perspective view of a locking device employed with my invention; Fig. 4 is a view partly in section of the lower portion of the bushing of Fig. 1 illustrating the condition of the fuse device upon operation thereof, and Fig. 5 is a sectional view of the portion of the bushing illustrated in Fig. 4 showing a modification of my invention.

Although my invention may be employed in the protection of electrical apparatus other than transformers, I have elected for the purpose of describing and illustrating my invention to show it as applied to the protection of an electric translating apparatus such as a transformer.

Referring now to the drawing, 1 indicates the casing of an electric translating apparatus, such as a transformer, which may contain the usual windings and insulating liquid dielectric. Casing 1 may be provided with a cover 2 suitably fastened thereto. Supported on cover 2 and extending from the top thereof is at least one insulated high voltage bushing 3 through which electrical connections with the high voltage windings of the transformer may be made. The bushing 3, preferably formed of porcelain or the like, is provided with an axially extending passageway or chamber 4 through which the high voltage lead extends so that connections may be made with an external electrical circuit. The bushing 3, preferably constructed of a ceramic insulating material, includes a depending portion 5 which extends for some distance beneath the cover 2 of casing 1 and in fact, as indicated in Fig. 1, extends below the normal level of the liquid dielectric contained in casing 1.

The passageway or chamber 4 within bushing 3 is substantially of uniform cross section except for an annular recess 6 formed near the upper or external portion of the bushing, the purpose of which will become apparent as the following description proceeds. Also near the lower or internal end of bushing 3, there are provided a plurality of annular recesses 7, the purpose of which will also become apparent from the following description.

In order to provide a readily removable or renewable bushing fuse, it is desirable to provide a lower contact in bushing 3 which may be removably connected with the fuse device to be

described hereinafter. I have illustrated a construction by way of example only and it will occur to those skilled in the art that the lower contact may be held in the bushing by any suitable means such as clamping, cementing, or the like. In the illustrated construction this lower contact member, indicated at 8 in Fig. 1, comprises a resilient sheet of conducting material having the upper and lower ends thereof displaced at a slight angle indicated at 9 in Fig. 2 and with a plurality of prongs 10 cut from the upper edge thereof and deflected a somewhat greater amount, as indicated in Fig. 1. A plurality of prongs 11 integral with contact 8, similar to the prongs 10, are provided along the lower edge of contact 8, which are deflected in the same direction as prongs 10, as is clearly shown in Fig. 1. An extension 12 to which an electrical conductor, such as 13 may be connected, is integrally formed with contact 8. Contact 8, which tends to be in the form of a sheet when free of bushing 3, is adapted to be rolled into cylindrical form and inserted into the lower or internal end of bushing 3 so that the prongs 10 and 11 spring into recesses 7 thereby holding lower contact 8 in position in bushing 3. By virtue of the deflected portions 9 upper and lower diverging entrance portions to the cylindrical contact 8 are provided, enabling the terminal of the fuse device to be readily inserted therein and removed therefrom. The insulated conductor 13 is preferably permanently connected as by welding or soldering with extension 12. It will be understood that insulated conductor 13 is connected to the high voltage winding of the transformer or translating apparatus.

The fuse device of my invention may be very similar to the fuse device disclosed in the above mentioned Smith patent except that conductor 13 must be permanently fastened to contact 8 and thus cannot move away with a suitable end cap to elongate the arc in the liquid dielectric as was done by Smith. However, this is accomplished in a new and novel manner as hereinafter described. As illustrated, this fuse device comprises a tube 14 of insulating material. The lower end of fuse tube 14 is closed by a cap 15 provided with a vent 16 so that liquid dielectric may enter fuse tube 14. The lower end of fuse tube 14 is also provided with an annular terminal or contact ring 17 which is electrically connected to cap 15 by a conductor 18 which is suitably covered with insulating material so the arc that forms between the burned end of the fuse element 20 in the fuse tube 14 and the cap 15 cannot strike thereto when the cap 15 is blown from the end of the tube 14 as illustrated in Fig. 4. The conductor preferably has considerable length and is coiled about the lower end of the fuse tube as indicated at 19 so cap 15 will continue to be electrically connected to contact ring 17 when blown from the end of the fuse tube 14 and thus can elongate the arc in the liquid dielectric. Mounted within the lower end of fuse tube 14 is a fusible element 20 electrically connected to end cap 15 at one end thereof, while the other end is electrically connected to a suitably insulated lead 21 terminating in a threaded terminal 22, and extending out of the upper end of fuse tube 14. Preferably the fuse tube 14 is vented in any suitable manner so that the liquid dielectric may freely enter through vent 16. This venting may be accomplished, for example, by the provision of a lock washer 23 closing the upper end of fuse tube 14, with the

discontinuous portion of the lock washer providing the vent.

In order to seal the passageway at the external end of bushing 3 it is desirable to provide means for locking the fuse device comprising fuse tube 13 in passageway 4. To this end I provide resilient locking means comprising a washer 24 having a plurality of resilient prongs 25, best shown in Fig. 3. Washer 24 is adapted to be placed over threaded terminal 22 of the fuse device with the prongs extending in an upward direction. A terminal and sealing member 26 for the transformer or electrical apparatus, having a female threaded portion 27, is adapted threadedly to engage terminal 22 whereupon prongs 25 of the locking washer 24 are spread into the annular recess 6 effectively locking the fuse device in passageway 4. Terminal 26 is also provided with a circumferential flange 28 adapted to cooperate with a sealing gasket 29 effectively to seal the upper end of passageway 4. While terminal 26 and flange 28 are shown as a unitary part they could be made as separate parts and arranged so that terminal 26 need not be turned in order to seal the upper passageway and thus the conductor which normally would be attached to terminal 26 need not be removed.

Upon rupture of the fusible element the expulsion action of the fuse device will cause cap 15 to blow off in the manner indicated in Fig. 4 so as effectively to interrupt the circuit by elongating the arc in the liquid dielectric since the arc must follow the cap 15 because the insulation on conductor 18 prevents it striking to conductor 18. By the construction hereinbefore described the quick elongation of the arc is made practical and yet a new fuse device may readily be inserted in the field by merely unscrewing terminal and sealing member 26 whereupon the prongs 25 of the locking device 24 spring inwardly and the old fuse device may be removed and a new one inserted.

In Fig. 5 I have illustrated a modification of my invention in which a slightly different fuse device is employed comprising a fuse tube 30. Corresponding parts of Fig. 5 are designated by the same reference numerals as in the preceding figures. Instead of fusible element 20 being connected electrically to cap 33 it extends through cap 33 around the end of the fuse tube and is connected to end 32 of lower fuse terminal 31. Lower fuse terminal 31 which engages contact 8 is spring biased so end 32 of terminal 31 will move away from fuse tube 30, to the dotted position indicated, when end cap 33 is blown free by the explosive action of the fuse device. Lower fuse terminal 31 is restrained from movement by engagement with cap 33 at end 32 as illustrated in Fig. 5 so no strain from its biasing means which is preferably inherent in terminal 31 is exerted on fusible element 30. End cap 33, which is provided with a vent 34 through which fusible element 20 extends, may be formed of any suitable insulating material, such as fiber, so when it falls to the bottom of the transformer tank upon being blown from fuse tube 30 it will not detrimentally affect the future operation of the transformer. The arc is elongated in the liquid dielectric quickly to interrupt the circuit by movement of end 32 of fuse terminal 31 after end cap 33 is blown off instead of by movement of end cap 15 at the end of flexible conductor 18 as in Fig. 4. It will be appreciated by one skilled in the art that end cap 33 in Fig. 5 could be omitted and end 32 of fuse terminal 31 could be releas-

ably latched to the end of fuse tube 28 or a strain wire could be used connected in parallel with fusible element 28 so as to relieve the fusible element 28 from the stress of the bias which otherwise might cause it to be damaged or stretched to the breaking point during normal operation.

From the above discussion it will be obvious that I have provided renewable bushing fuses which provide for elongation of the arc in the liquid dielectric quickly to interrupt the circuit, which is readily replaceable in the field, and consequently may be more widely used since the current rating thereof need not be so high as to be blown only in the event of an internal fault on the electrical apparatus.

While I have shown and described my invention in connection with certain specific embodiments, it should be understood that my invention is not limited to the specific details herein illustrated, and that changes and modifications may occur to one skilled in the art without departing from the spirit and scope of my invention as set forth in the appended claims.

What I claim as new and desire to secure by Letters Patent of the United States is:

1. In combination, an electrical device including a high voltage bushing, a passageway in said bushing, an annular recess in said bushing adjoining said passageway, a renewable bushing fuse having a terminal adapted to be inserted in said passageway, a locking member insertable in said passageway having an opening therein through which said terminal extends, and means adapted to threadedly engage said terminal for forcing said locking member into said recess to hold said fuse immovable in said passageway whereby the end of said passageway at the external end of said bushing may be sealed, said locking member being resilient and positioned relative to said bushing fuse, passageway and recess for release therefrom upon disengagement of said means from said terminal.

2. In combination with an electrical device including a high voltage bushing, a passageway in said bushing, an annular recess in said bushing adjoining said passageway near the external end of said bushing, a renewable bushing fuse having a terminal adapted to be inserted in said passageway, a washer with prongs insertable in said passageway so that said terminal extends therethrough, and means adapted to threadedly engage said terminal for forcing said prongs into said recess to hold said fuse immovable in said passageway and for sealing the end of said passageway at the external end of said bushing, said prongs being resilient and positioned relative to said bushing fuse, passageway and recess for release therefrom upon disengagement of said means from said terminal.

3. A renewable bushing fuse device for electric apparatus of the type employing a liquid dielectric and including a high voltage bushing with a passageway for said fuse device in said bushing, comprising a fuse tube of insulating material, terminals mounted on said fuse tube, a fusible element in said fuse tube electrically interconnecting said terminals, a coacting terminal engageable with one of said fuse tube terminals, locking means in said passageway having resilient portions engageable with said coacting terminal upon movement thereof in one direction relative to the fuse terminal for rendering said bushing fuse immovable in said passageway and upon movement in the opposite direction to release said locking means for rendering the bushing fuse re-

movable from said passageway, and sealing means around said coacting terminal for simultaneously sealing one end of said passageway when the terminal is moved in the direction to effect the locking action of said locking means.

4. A renewable bushing fuse device for electric apparatus of the type employing a liquid dielectric and including a high voltage bushing with a passageway for said fuse device in said bushing, comprising a fuse tube of insulating material, terminals mounted on said fuse tube, a fusible element in said fuse tube electrically interconnecting said terminals, a resilient contact supported within said passageway so as to be electrically connected with one of said terminals when said fuse device is in said passageway, a coacting terminal engageable with one of said fuse tube terminals, locking means in said passageway having resilient portions engageable with said coacting terminal upon movement thereof in one direction relative to the fuse terminal for rendering said bushing fuse immovable in said passageway and upon movement in the opposite direction to release said locking means for rendering the bushing fuse removable from said passageway, and sealing means around said coacting terminal for simultaneously sealing one end of said passageway when the terminal is moved in the direction to effect the locking action of said locking means.

5. A renewable bushing fuse device for electric apparatus of the type employing a liquid dielectric and including a high voltage bushing with a passageway for said fuse device in said bushing, comprising a fuse tube of insulating material, terminals mounted on said fuse tube, a fusible element in said fuse tube electrically interconnecting said terminals, a coacting terminal engageable with one of said fuse tube terminals, locking means in said passageway having resilient portions engageable with said coacting terminal upon movement thereof in one direction relative to the fuse terminal for rendering said bushing fuse immovable either axially or radially in said passageway and upon movement in the opposite direction to release said locking means for rendering the bushing fuse removable from said passageway, and means coacting with said releasable locking means for simultaneously sealing one end of said passageway when the coacting terminal is moved in the direction to effect the locking action of said locking means.

6. A renewable expulsion bushing fuse device for electric apparatus of the type employing a liquid dielectric and including a high voltage bushing with a passageway for said fuse device in said bushing, comprising a fuse tube of insulating material, an axial terminal mounted partially within and at one end of said fuse tube, a coaxial terminal mounted outside of and closely adjacent the opposite end of said fuse tube, a fusible element located in said fuse tube closely adjacent said opposite end and electrically interconnecting said terminals, means mounted adjacent said fusible element at said opposite end and renewable with said fuse device for quickly elongating the arc in the liquid dielectric when said fusible element is melted, a coacting terminal engageable with said axial terminal, locking means in said passageway having resilient portions engageable with said coacting terminal upon movement thereof in one direction relative to the axial terminal for rendering said bushing fuse immovable in said passageway and upon movement in the opposite direction to release said

7 locking means for rendering the bushing fuse removable from said passageway, and means for sealing one end of said passageway.

7. A renewable expulsion fuse device for electric apparatus of the type employing a liquid dielectric and including a high voltage bushing with a passageway for said fuse device in said bushing, comprising a fuse tube of insulating material, an axial terminal mounted partially within and at one end of said fuse tube, a coaxial terminal mounted outside of and closely adjacent the opposite end of said fuse tube, a fusible element located in said fuse tube closely adjacent said terminals, a resilient contact supported within said passageway so as to be electrically connected with one of said terminals when said fuse device is in said passageway, a coacting terminal engageable with said axial terminal, locking means in said passageway having resilient portions engageable with said coacting terminal upon movement thereof in one direction relative to the axial terminal for rendering said bushing fuse immovable in said passageway and upon movement in the opposite direction to release said locking means for rendering the bushing fuse removable from said passageway, sealing means around said coacting terminal for simultaneously sealing one end of said passageway when the terminal is moved in the direction to effect the locking action of said locking means, an end cap for said tube adapted to be blown free from said tube upon rupture of said fusible element by the expulsion action of said fuse device, and insulated means mounted adjacent said fusible element at said opposite end for maintaining electrical contact between said cap and said coaxial terminal so as to elongate and quickly extinguish the arc formed upon rupture of the fusible element.

8. A renewable expulsion fuse device for electric apparatus of the type employing a liquid dielectric and including a high voltage bushing with a passageway for said fuse device in said bushing, comprising a fuse tube of insulating material, an axial terminal mounted partially within and at one end of said fuse tube, a coaxial terminal

8 mounted outside of and closely adjacent the opposite end of said fuse tube, a fusible element located in said fuse tube closely adjacent said opposite end and electrically interconnecting said terminals, a resilient contact supported within said passageway so as to be electrically connected with one of said terminals when said fuse device is in said passageway, a coacting terminal engageable with said axial terminal, locking means in said passageway having resilient portions engageable with said coacting terminal upon movement thereof in one direction relative to the axial terminal for rendering said bushing fuse immovable in said passageway and upon movement in the opposite direction to release said locking means for rendering the bushing fuse removable from said passageway, sealing means around said coacting terminal for simultaneously sealing one end of said passageway when the terminal is moved in the direction to effect the locking action of said locking means, an end cap for said tube adapted to be blown free from said tube upon rupture of said fusible element by the expulsion action of said fuse device, and means mounted adjacent said fusible element at said opposite end and associated with the blowing off of said cap for quickly elongating and extinguishing the arc formed upon rupture of said fusible element.
